UNITED STATES PATENT OFFICE.

WILLIAM M. KURTZ, OF COLUMBUS, OHIO.

STRAP-HINGE.

SPECIFICATION forming part of Letters Patent No. 257,022, dated April 25, 1882.

Application filed June 3, 1881. (No model.)

To all whom it may concern:

Be it known that I, WILLIAM M. KURTZ, of Columbus, in the State of Ohio, have invented certain new and useful Improvements in Strap-Hinges, of which the following is a specification.

It is my object to obtain a stronger strap-hinge than the ordinary strap-hinge of commerce without increasing the size of the hinge or materially enhancing the cost of manufacture. To this end, in lieu of providing both strap-leaves with the ordinary tubular knuckles which receive the pintle, I form one of the leaves with side ears or flanges which stand at right angles to the body of the strap-leaf, and are formed with holes to receive the pintle, the said ears and the body of the strap-leaf being made out of one piece of metal. The other strap-leaf is provided with a knuckle which encircles the pintle, and is held between the upturned ears or flanges of the first leaf, and with the pintle and the ears or flanges which receive it I combine independent external re-enforcing blocks, which receive the outer ends of the pintle, are bolted or fastened to the structure to which the flanged leaf is secured, and serve to support, re-enforce, and strengthen the ears.

The nature of my invention and the manner in which the same is or may be carried into effect will be understood by reference to the accompanying drawings, in which—

Figure 1 is a perspective view of a strap-hinge embodying my improvements in their preferred form. Fig. 2 is a section on the line 1 1, Fig. 1. Fig. 3 is a view of the flanged strap-leaf. Fig. 4 is a view of one of the strengthening blocks or pieces.

A is the strap-leaf which receives and holds the pintle. It is for this purpose formed out of one piece of metal, with upturned side ears or flanges b at its front end, which ears are perforated, as shown, to receive the pintle a. The other leaf, B, is formed with a tubular knuckle, c, which fits snugly between the two

ears b, and is there held by the pintle a, which, after passing through the ears and the knuckle, has its ends upset or otherwise enlarged, so as to bind all parts firmly together, preventing the ears from spreading without, however, cramping the knuckle c to such an extent as to prevent it from turning upon the pintle. In this way a strap-hinge is obtained which possesses about twice the strength of the ordinary strap-hinge of the same size, and can be manufactured almost as cheaply as the latter.

For the purpose of re-enforcing the ears or flanges b, I place outside of said ears or flanges separate and independent supporting blocks or pieces C, preferably of wrought iron or malleable metal, which are secured to the same structure to which the leaf A is fastened, and receive the outer ends of the pintle, which should, as shown, be of such length as to pass through and project at each end beyond the blocks C. The pintle is supported and held by both the ears and the blocks, and the latter by the rivet are drawn up against the ears, re-enforcing and supporting them and adding appreciably to the strength and durability of the hinge.

Having described my improvements, what I claim, and desire to secure by Letters Patent, is—

A strap-hinge consisting of a strap-leaf provided with upturned side ears or flanges, and separate and independent re-enforcing-blocks external to said ears, in combination with a strap-leaf formed with a tubular knuckle received between the two ears of the other leaf, and a pintle which passes through said knuckle, ears, and external re-enforcing blocks, under the arrangement and for operation as hereinbefore shown and described.

In testimony whereof I have hereunto set my hand this 31st day of May, 1881.

WILLIAM M. KURTZ.
